UNITED STATES PATENT OFFICE.

ROYDON LEE FRIEND, OF CONNERSVILLE, INDIANA, ASSIGNOR TO THE P. H. & F. M. ROOTS COMPANY, OF CONNERSVILLE, INDIANA, A CORPORATION OF INDIANA.

CUPOLA CHARGER.

Application filed September 15, 1923. Serial No. 662,826.

The present invention relates to conveying and hoisting apparatus and is designed especially for use in charging iron, coke and other materials into a foundry cupola. In the operation of a cupola it is desirable to collect the material from storage spaces and deposit it in the cupola as economically and with as little labor as possible. It is also desirable to drop the material centrally in the cupola onto the fuel bed in order to distribute the material evenly and to prevent bridging and uneven accumulations of material in the lower part of the cupola. In many foundries local conditions make it impractical so to design the apparatus that the charger by which the material is deposited in the cupola may travel to a distant storage space to collect material; and in such situations it is desirable that the charger be capable of collecting material from as extensive an area immediately adjacent the cupola as possible. The principal object of the present invention is the provision of apparatus adapted to collect material from an extensive area adjacent the cupola and to deposit the material centrally within a cupola. The invention also comprehends the details of construction of the apparatus.

In the drawings, which illustrate a preferred embodiment of the invention:

Figure 1 is a side elevation of apparatus embodying the invention.

Figure 2 is an enlarged detail of one part of the apparatus.

Figure 3 is a section on the line 3—3 in Figure 2, and

Figure 4 is an enlarged section on the line 4—4 in Figure 1.

Iron, coke and other material is to be collected and deposited in the cupola 1 by the charger 2 which travels rectilinearly on a suspended track 3 which is preferably an I-rail. The charger 2 comprises a hollow cantilever arm 4 adapted to have its forward end projected into a position centrally within the cupola so that material may be dropped onto the fuel bed and evenly distributed over the bed. A hoisting drum 5 is mounted within the arm and is operable by a motor 6. A hoisting cable 7 coiled on the drum 5 extends through the forward end of the arm 4 and supports a carrier by which material is collected and deposited in the cupola. For the collection of iron the car-

rier is a magnet 9 controlled by a conductor 55 8 coiled on the drum 5 with the cable 7, while coke and other material will be collected by a bucket supported from the cable 7. The charger 2 is supported from the track 3 by wheels 10 and 11 travelling on the lower flange of the track and the charger is movable along the track by a motor 12 geared to drive certain of the wheels, as the wheels 10.

In order that the charger, which may travel along the rectilinear track 3, may collect material from as extensive an area as possible adjacent the cupola, the track 3 is mounted so as to be capable of rotation on a vertical axis. A circular track 13, which is preferably a circular I-rail, is supported from the frame 14. A bevel gear 15 is secured to the frame concentrically with the track 13, and secured in the hub 16 of the gear is a support 17 formed at its depending lower end with a head 18. A two part clamp 19, whose halves are secured together by bolts 20, is carried on a bearing 21 supported on the head 18, and the halves of the clamp are formed on their inner faces with recesses 22 engaging the upper flanges of the track 3.

The track 3 is provided adjacent its opposite ends with trucks in which are journaled wheels travelling on the circular track 13. 85 Each of the trucks comprises two similar members 23 secured together by bolts 24 and provided on their inner faces with recesses 25 fitting over the upper flanges of the track 3. In each half of the truck there is secured a shaft 26 on which is journaled a wheel 27 travelling on a lower flange of the circular track 13.

The track 3 may be rotated by a motor 28 mounted on the track 3 and connected by suitable gears with the fixed circular bevel gear 15. The motor 28 and also the motors 6 and 12, are preferably controlled by controllers mounted in a cage carried by the charger 2 as diagrammatically illustrated in Figure 1. The motors may, if desired, be controlled by an operator on the floor by means of depending cables or they may be controlled from a single fixed station, such as a pulpit, from which the operator may observe the cupola and the entire operating area.

In operation the track 3 will be rotated

and the charger will be moved along the track until the carrier at the forward end of the charger is located over the material to be collected. The carrier will then be lowered and raised to collect and hoist a charge of material, whereupon the track 3 will be rotated and the charger travelled along the track to project the carrier at the forward end of the charger into central position within the cupola, when the charge of material will be dropped onto the fuel bed. Although the entire apparatus is relatively compact the invention makes it possible to collect material from an extensive storage area by rotation of the track 3 through an angle of three hundred and sixty degrees or more and by travel of the charger diametrically of the circle. The rotation of the track, the travel of the charger and the operation of the hoisting drum, as well as the control of the magnet when one is used as the carrier, may be conveniently and centrally controlled preferably by an operator in the cage carried by the charger. The detailed construction by which the track 3 is rotatably supported by the frame and by the circular track provides not only for simplicity of manufacture of the parts involved, but for very easy assembly of the apparatus and for very sturdy support of the charger.

Having thus described my invention, what I claim is:—

1. In an over-head railway for cranes and the like, an elevated circular track, a rectilineal track supported centrally by a pivot bearing and adjacent its ends by said circular track, and means for driving said rectilineal track along said circular track.

2. In an over-head railway for cranes and the like, a circular I-section track, and a rectilineal I-section track extending across said circular track and dependingly supported therefrom at their points of crossing for movement therealong, a pivotal support for said rectilineal track midway of its length between said circumferential points and means adjacent said pivotal support for moving said rectilineal track to any circumferential position with respect to said pivotal support.

3. In an over-head track system, the combination of an elevated circular I-section track, an I-section track extending diametrically of the circular track, wheels secured to the second track adjacent its ends and travelling on the circular track on the lower flanges of said I-section, and an anti-friction bearing concentric with the circular track supporting the second track and whereby said second track may be rotated to any diameter of said circular track.

4. In an over-head railway for cranes and the like, a circular I-section track, and a rectilineal I-section track extending across

said circular track and dependingly supported therefrom at a plurality of circumferential points for movement therealong.

5. In an over-head railway for cranes and the like, a circular I-section track, and a rectilineal I-section track extending across said circular track and dependingly supported therefrom at a plurality of circumferential points for movement therealong, and a pivotal support for said rectilineal track midway of its length between said circumferential points. 70 75

6. In an over-head track system, the combination of an elevated circular track, a track extending diametrically of the circular track, wheels secured to the second track adjacent its ends and travelling on the circular track, and an anti-friction bearing concentric with the circular track supporting the second track. 80 85

7. In an over-head track system, the combination of a frame, an elevated circular track secured thereto, a track extending diametrically of the circular track, wheels secured to the second track adjacent its ends and travelling on the circular track, a support and a circular gear secured to the frame concentrically with the circular track, an anti-friction bearing supporting the second track from the support, and a motor carried by the second track geared to the circular gear. 90 95

8. In an over-head track system, the combination of a frame, an elevated circular I-rail secured thereto, an I-rail extending diametrically of the circular rail, trucks respectively secured to the second rail adjacent its ends, each truck comprising two members clamped together and formed on their inner faces with recesses engaging the upper flanges of the second rail, wheels journaled in the trucks and travelling on the circular rail, a support depending from the frame concentrically with the circular track and having an anti-friction bearing, and a clamp resting on the bearing and formed with recesses engaging the upper flanges of the second rail. 100 105 110 115

9. In an elevated track system, the combination of a frame, an elevated circular I-rail secured thereto, an I-rail extending diametrically of the circular rail, trucks respectively secured to the second rail adjacent its ends, each truck comprising two members clamped together and formed on their inner faces with recesses engaging the upper flanges of the second rail, wheels journaled in the trucks and travelling on the circular rail, a support depending from the frame concentrically with the circular track and having an anti-friction bearing, a clamp resting on the bearing and formed with recesses engaging the upper flanges of the second rail, a circular gear secured to the frame concentrically with the circular 120 125 130

rail, and a motor carried by the second rail geared to the circular gear.

10. The combination of a circular I-rail, an I-rail extending diametrically of the circular rail, trucks respectively secured to the second rail adjacent its ends, each truck comprising two members clamped together and formed on their inner faces with recesses engaging the upper flanges of the second rail, wheels journaled in the trucks and

travelling on the circular rail, a fixed support concentric with the circular track and having an anti-friction bearing, and a clamp resting on the bearing and formed with recesses engaging the upper flanges of ¹⁵ the second rail.

In witness whereof, I hereunto subscribe my name this 12th day of September, 1923.

ROYDON LEE FRIEND.
